UNITED STATES PATENT OFFICE.

ROE C. HAWKINS, OF LONG BEACH, CALIFORNIA, ASSIGNOR TO "H H" MANUFACTURERS, INC., OF LONG BEACH, CALIFORNIA, A CORPORATION OF CALIFORNIA.

GROUSER.

Application filed July 9, 1925. Serial No. 42,461.

My invention is a grouser adapted to be attached to the tractor wheels of a farm tractor or similar machine and is adapted to form a readily removable or if desired a permanent grouser.

5 The grouser illustrated is particularly designed to fit on the wheel of the Fordson tractor and to clamp to the present cleats which extend crosswise in a diagonal direction 10 of the rim of the wheel. My grouser has a pair of concave faced lugs connected by a web formed at an angle to the faces of the lugs for attachment to a cleat. The grouser is specially designed to penetrate 15 hard soil and to also give sufficient traction in sand or mud, and on account of the concave faces does not clog with mud or adobe.

20 My invention will be more readily understood from the following description and drawings in which:

Figure 1 is a perspective elevation of a tractor wheel with my grouser attached thereto.

25 Fig. 2 is a plan view of one of the grousers attached to a cleat taken in the direction of the arrow 2 of Fig. 1.

Fig. 3 is an end elevation of the outside edge of the grouser taken in the direction of the arrow 3 of Fig. 2.

30 Fig. 4 is an elevation of a section of the tractor wheel viewed in the direction of the arrow 6 of Fig. 1, showing the action of the grouser in entering and leaving the soil.

Fig. 5 is a plan view of an alternative 35 form in which the grousers are in the form of double lugs without a connecting web.

In the drawings, a tractor wheel is designated generally by the numeral 1 and has secured to its face, cleats 2, having a flat web 3 40 bolted to the rim 4 of the wheel and having an outstanding flange 5 with bolt holes 6 therein.

The grouser has two projecting lugs 8 and 9 and a web section 10 therebetween. The rear face of the lugs and the web are formed 45 with a plain surface 11 adapted to fit the flange of the cleats. As these cleats are placed on the tractor wheel at an angle the faces 12 and 13 of the lugs are formed to make substantially a right angle with the rim of the wheel, that is, with the direction 50 of travel of the tractor. The end walls 14 and 15 are therefore considerably wider than the side wall 16 of the outside lug. A recess 17 is formed in the face of the lug 8 and 55 a recess 18 in the rear wall 15 of the lug 9.

These recesses are to accommodate the heads 19 of the bolts 20 secured through the bolt holes 6 and thus clamp the grousers securely to the cleats.

My grouser is made with a fairly sharp 60 cutting edge 21 at the extreme outside of the lugs, the base 22 fitting against the rim of the wheel is of considerable width to properly transmit the pressure to the wheel rim without cracking same. The faces 12 65 and 13 are made concave, the upper portion 23 being curved on the radius of a much larger diameter than the lower portion 24 so as to give a relatively sharp curve and form an acute angle 25 where the tip of the 70 lug meets the rim of the wheel.

The manner of attachment of the grouser will be apparent from the above description and as the bolts are readily accessible the grousers may be quickly detached from the 75 cleats or may be left permanently attached thereto.

The action of the grousers in operation will be more readily apparent from Fig. 4 in which the soil is designated generally by 80 the numeral 26, 27 being the surface thereof. The tractor is moving forward and it will be noticed that a leading grouser 28 projects somewhat forward of the tip 25 of the base of the grouser and cuts into hard 85 soil on account of the sharp cutting edge 21, compacting the soil on the curved concave face as indicated by the numeral 29. If any soil should have clogged on the grouser lugs, it is forced off by the compressing action of 90 the soil. The mid-positioned grouser 30 will bear considerable weight of the tractor and facilitate this clearing action. The trailing grouser 31, on account of the curved faces 12 and 13, pulls out of the soil without lifting 95 clods and allows the surface of the ground to fall backwardly into the hole dug by the grouser lugs with comparatively little disturbance to the soil. Hence a tractor equipped with my grousers does not form 100 deep furrows throwing the soil to one side as is one of the difficulties experienced with many types of grousers.

It will be apparent that the particular form of grouser lugs may be materially 105 changed to suit different types of tractors used, and that the cleat or the equivalent may be cast integral with the grouser. Many other modifications of the design will be apparent such as changes of the curves 110

of the faces, widening of the grouser lugs and so on to suit special requirements. Moreover, my grouser does not require a base 22 of great width, except to form the proper curve to the face as the lugs do not have a great levering action on the rim and therefore do not break sections out as is sometimes a common occurrence with grousers attached directly to the rims of tractor 10 wheels.

In Fig. 5, the grousers 35 and 36 are in the form of double lugs without any connecting web and each are separately bolted to the upstanding flange 5 of the cleats 2. These 15 lugs have the same characteristic as those shown in the other illustrations having the working faces substantially square to the direction of rotation of the wheel and with the back faces at an angle to conform with the 20 diagonal position of the cleats on the rim of the wheel.

Having described my invention, what I claim is:

1. A grouser having a plurality of up- 25 standing lugs, said lugs having bases adapted to contact with a tractor wheel and conform to the shape thereof, a web portion of reduced height between each pair of lugs and bolt holes through the lugs adapted to 30 secure bolts to a supporting device on a tractor wheel.

2. A grouser having a plurality of up- 35 standing lugs, said lugs being adapted to bear directly on the periphery of a wheel, a web of less height than the lugs connecting the lugs, the back of the lugs and the web forming substantially a plain surface and means to attach the grouser to a tractor wheel.

40 3. A grouser as claimed in claim 2, in which the face of each lug is formed at an angle to the face of the web, adapting said face to be substantially crosswise of a tractor wheel with the web at an angle thereto.

45 4. A grouser as claimed in claim 2, in which the lugs have a base adapted to contact with a tractor wheel rim, a somewhat

sharpened penetrating edge and a concaved curve between the tip of the base and the cutting edge on the face of the lugs. 50

5. A tractor wheel having in combination a wheel rim, an angular cleat attached thereto, a grouser bolted to the cleat, said grouser having a plurality of lugs extending outwardly beyond the cleat, the lugs having a base resting on the rim of the wheel, a web connecting the lugs, the web being substantially of the same height as the cleat. 55

6. A tractor wheel as claimed in claim 5, in which the lugs have a pair of recesses 60 adapted to engage the heads of bolts, said lugs being formed with faces angularly positioned in regard to the web.

7. A tractor wheel as claimed in claim 5, in which the bases of the lugs are of considerable extent along the rim of the wheel and the penetrating edge of each lug forms a cutting edge, the face of each lug having a concaved curve from its cutting edge to the tip of its base. 70

8. A tractor wheel as claimed in claim 5, the grouser lugs having faces at an angle to the web adapted to be substantially at right angles to the rim, a recess in the face of one of the lugs to engage a bolt head and a recess 75 in the end wall of the other lug to engage a second bolt head.

9. A tractor wheel having in combination a wheel rim, a cleat attached thereto having a face extending diagonally across the wheel 80 rim, a grouser having a pair of lugs connected by a web, the back of the lugs and the back of the web being in substantially the same plane and fitting against the cleat, lugs having bases resting on and extending partially along the face of the rim, the lugs extending outwardly from the rim a greater distance than the cleat and the web, the front faces of the lugs extending square across the 85 wheel rim and means to fasten the grouser 90 to the cleat.

In testimony whereof I have signed my name to this specification.

ROE C. HAWKINS.
